(57) **CLAIM**

The ornamental design for a specimen collection tray, as shown and described.

DESCRIPTION

FIG. 1 is a front, top, left side perspective view of a specimen collection tray.

FIG. 2 is a rear, bottom, right side perspective view of the specimen collection tray of FIG. 1.

FIG. 3 is a left side view of the specimen collection tray of FIG. 1.

FIG. 4 is a right side view of the specimen collection tray of FIG. 1.

FIG. 5 is a bottom view of the specimen collection tray of FIG. 1.

FIG. 6 is a top view of the specimen collection tray of FIG. 1.

FIG. 7 is a front view of the specimen collection tray of FIG. 1; and,

FIG. 8 is a rear view of the specimen collection tray of FIG. 1.

The broken lines in the drawings depict portions of the specimen collection tray that form no part of the claimed design.

1 Claim, 4 Drawing Sheets
